UNITED STATES PATENT OFFICE

ELDEN ELMO BROWN, OF HENNESSEY, OKLAHOMA

GASEOUS FUEL MIXING DEVICE

Application filed August 2, 1929. Serial No. 382,901.

This invention relates to internal combustion engines, and has more particular reference to a device adapted to be attached to an internal combustion engine, and in communication with the intake of the engine and the outlet port of the carburetor to provide a passage of the mixed fuel from the carburetor to the engine, the device further comprehending the provision of means within 5 this passage for thoroughly drying the mixed fuel prior to its discharge into the internal combustion engine.

The invention has as its primary object the provision of a device of this nature, consisting of a casing having an inlet port in communication with the outlet of the carburetor, and an outlet port in communication with the intake of the internal combustion engine together with a rotatably mounted member 10 within the casing, the member comprising a casting having a plurality of passages whereby the mixed fuel from the carburetor must pass therethrough prior to its discharge into the intake of the internal combustion engine, the casing being provided at one end and having formed integral therewith a plurality of spaced blades radiating from a central opening formed in said side or end of the casting, the central opening constituting the 15 intake port common to all of the fluid conducting passages.

A still further object of the invention is to provide in a device of this character, a unit of the nature above mentioned, the unit further embodying a plurality of circumferentially spaced radial blades formed on the outer circumference of the casting to facilitate the return through the casing that portion of the mixture which has not been sufficiently dried with the result that this portion of the mixture may again co-mingle with the incoming mixture from the carburetor to again undergo the process of drying.

A still further object of the invention is 20 to provide a gaseous fuel mixing device of

this nature, which is comparatively simple in construction, strong, durable, thoroughly reliable, practical and efficient in operation, and otherwise well adapted for the purpose designed.

Other objects and advantages of the invention will become apparent during a study of the following description, taken in connection with the accompanying drawings wherein:

Figure 1 is a longitudinal sectional view taken through the device constructed in accordance with this invention.

Figure 2 is a vertical transverse sectional view taken substantially on the line 2—2 of Figure 1.

Figure 3 is a view similar to Figure 2 and taken on the line 3—3 of Figure 1.

Figure 4 is a side elevation of the drier per se.

With reference more in detail to the drawings, it will be seen that my device consists essentially of an open-ended cylindrical casing 5 which casing tapers longitudinally as at 6 toward its reduced discharge end 7. At its reduced discharge end 7 the casing is provided with an annular outstanding flange 8. Thus it will be seen that at its relatively wider end the casing is closed and the end wall of the casing has a central flange or extension 9 formed therein which is apertured to form a bearing for the shaft 10 which extends longitudinally through the casing 5 and is suitably driven by suitable means and of course at any desired speed as to be determined by the discretion of the user.

That portion of the shaft which extends into the casing 5 has mounted thereon a rotor designated generally by the reference character 11. The specific construction and purpose of this rotor will be hereinafter more fully described. On the bottom wall of the casing and adjacent the larger end of the casing, the same is provided with an intake opening 12, from which opening depends a

tubular neck 13, suitably flanged at its lower end to facilitate the attachment thereof to the discharge of a carburetor.

The rotor unit 11 is in the nature of an especially constructed substantially circular cylindrical casting 14. Extending through the head from the forward to the rear side of the casting is a plurality of circumferentially disposed fluid passages 15. The walls 10 of the passages 15 provide circumferentially spaced separator vanes 16. At its inner side the casting 14 is provided with a centrally disposed intake opening 17 from which opening the passages 15 extend, the opening providing the common intake for these passages. It is to be noted that these passages are of somewhat arcuate configuration and radiate from said common opening 17 to merge with the outer peripheral edge of the unit or casting 14 as they continue to the forward face of the casting.

A plurality of annular screens 18 extend transversely through the passages 15 and these screens 18 are disposed in longitudinal 25 spaced relation. Obviously, the screens 18 graduate in diameter, the screen having the smallest diameter being the one nearest to the opening 17.

On its inner face the casting 14 is provided 30 with and has formed integral therewith circumferentially spaced substantially elongated curved fan blades 19, which blades 19, as shown to advantage in Figure 3 radiate from a common center opening 17. The blades 19 35 provide as it were a suction fan for the drier. It is to be noted that these blades 19 are so disposed within the casing 5 as to be in operative relation to the intake opening 12.

On its outer periphery the casting 14 is 40 provided with circumferentially spaced transverse fins 20 which fins 20 extend obliquely of the casting. Certain of the fins being curved as at 21.

Circumferentially arranged within the casing 5 at the closed end of the casing are spaced fins 22, which fins are disposed circumferentially about the casing from opposite sides of the intake opening 12. The blades 19 have their outer ends terminating in spaced relation to the outer longitudinal edges of the stationary fins 22, the purpose of the fins 22 being to prevent a whirling motion being imparted to the air within the casing.

Preferably, the bearing 9 is lubricated by 55 a suitable dope cup 9'. Obviously upon rotation of the shaft 10 the mixed fuel will be drawn into the casing 5 through the intake neck 13 and the discharge of the carburetor and will be drawn by suction through the 60 common intake opening 17, whereby it will be separated by the walls 16 to flow through the separate passages 15 to discharge from the passages at the forward end of the casting 14 and inwardly from the reduced end 65 or discharge opening of the casing 5.

Certain of the mixture discharging from the passages 15 will be drawn by suction into the intake of the internal combustion engine, as is obvious.

Of course, the rotative movement imparted 70 to the rotor 11 will thoroughly mix the fuel from the carburetor as it passes through the passages 15 and at the same time a greater portion of the fuel dried prior to being drawn into the intake of the engine. However, the remaining wet portion of the fuel accumulates in the bottom of the casing 5, this portion of the fuel then being directed due to the slope provided by the tapered end 6 towards the intake of the casing to co-mingle 75 with the incoming fuel to once again undergo the process previously undergone.

Further, the fin 20 will assist in forcing this portion of the fuel towards the said intake and at the same time acting upon this portion of the fuel for mixing and drying the 85 same.

Bolted or otherwise secured to the flange 8 of the casing 5 is an annulus or ring 24 as at 90 23. This ring 24 is provided on its inner face 90 and adjacent its inner peripheral edge with a groove 24'. The wall of the groove 24' at the inner circumferential edge of the ring 24 is a continuation of said edge and provides a somewhat sharpened edge 25. Thus the 95 mixed fuel discharging from the passages 15 coming in contact with this edge 25 is divided and broken up so that the sufficiently dried gases will be drawn to a fuel conductor pipe 26 formed integral with the ring 24 which 100 pipe 26 has its discharge end adapted to be connected to the intake of an internal combustion engine, while the intake end of the pipe 26 is in communication with the discharge opening of the casing 5 as will be 105 readily apparent from a study of Figure 1.

The groove 24' in the ring 24 provides as it were a return for the mixed fuel which after undergoing the drying process has not been sufficiently dried and which when separated from the dried gases through the medium of the member 25 is returned by way of the groove 24' to flow back to the casing 5 toward the intake end of the casing to be actuated during its course by the fins 20 for hastening its return to again mingle with the incoming mixture as has been hereinbefore fully described.

From the foregoing, it will be seen that a gaseous fuel mixing device of this nature may 120 be used on all internal combustion engines and that the same will not act as a super-charger for the engine, and that the rotor for drying the mixture consists of but one integral structure embodying the suction fan, 125 and the passages formed in the casting constituting as it were, a mixing bowl for the device.

Furthermore, a device of this nature will insure a thorough drying of the mixture, 130

which of course will result in an efficient operation of the motor to which a gaseous fuel mixing device constructed as comprehended by this invention is associated.

5 The present embodiment of the invention has been illustrated somewhat in detail merely as an exemplification, since in actual practice the device is susceptible to certain changes in construction, arrangement and materials 10 used coming within the spirit of the invention as described and claimed.

Having thus described my invention, what I wish to claim as new and secure by Letters Patent is:

15 1. In a device of the class described, a casing formed adjacent one end with means for attaching the casing to the discharge port of a carbureter, said casing being formed at its opposite end with means providing a 20 conduit adapted to be connected with the intake of an engine, a member rotatably mounted within the casing, said member comprising a plurality of fuel conducting passages formed therein and extending therethrough, 25 said member at one end being provided with an intake opening common to all of said passages, and blades formed integral with said member and radiating from said intake opening, said blades being disposed in operative 30 relation to the intake end of the casing.

2. In a device of the class described, a casing formed adjacent one end with means for attaching the casing to the discharge port of a carbureter, said casing being formed at its opposite end with means providing a conduit adapted to be connected with the intake of an engine, a member rotatably mounted within the casing, said 35 member comprising a plurality of fuel conducting passages formed therein and extending therethrough, said member at one end being provided with an intake opening common to all of said passages, blades formed integral with said member and radiating from said intake opening, said blades being disposed in operative 40 relation to the intake end of the casing and disposed in operative relation to the intake end of the casing, and means within the casing and disposed in operative relation to the discharge end of the passages for separating the fuel discharging from the passages whereby fuel under pressure may be diverted to return undried particles of the fuel to be again mixed with the incoming fuel mixture.

55 3. In a gaseous fuel mixing device for internal combustion engines, a cylindrical casing opened at one end, said casing tapering toward said one end to provide a restricted discharge opening, said casing being provided at its largest end with an intake opening adapted to register with the discharge port of a carbureter, the discharge end of the casing adapted to be connected to the intake of an internal combustion engine, a 60 member rotatably mounted within the cas-

ing, said member comprising a casting having a plurality of fuel conducting passages formed therein and extending from one end to the other through the casting, said casting being provided on its inner end with a central intake opening common to all of said passages, blades formed on said inner end of the casting, said blades radiating from said central opening, and fuel separating means located within the casing at the discharge end of the casing and in operative relation to the discharge end of the passages, whereby a portion of the fuel mixture under pressure may be diverted to be returned toward the intake opening in the casing to commingle with the incoming fuel mixture.

70 4. In a gaseous fuel mixing device for internal combustion engines, a cylindrical casing opened at one end, said casing tapering toward said one end to provide a restricted discharge opening, said casing being provided at its largest end with an intake opening adapted to register with the discharge port of a carbureter, the discharge end of the casing adapted to be connected to the intake of an internal combustion engine, a member rotatably mounted within the casing, said member comprising a casting having a plurality of fuel conducting passages formed therein and extending from one end to the other through the casting, said casting being provided on its inner end with a central intake opening common to all of said passages, blades formed on said inner end of the casting, said blades radiating from said central opening, and fuel separating means at the discharge end of the casing and in operative relation to the discharge ends of the passages, whereby a portion of the fuel mixture under pressure may be diverted to be returned toward the intake opening in the casing to commingle with the incoming fuel mixture, circumferentially spaced fins arranged within the casing at opposite sides of the intake opening in the casing.

75 5. In a gaseous fuel mixing device for internal combustion engines, a cylindrical casing opened at one end, said casing tapering toward said one end to provide a restricted discharge opening, said casing being provided at its largest end with an intake opening adapted to register with the discharge port of a carbureter, the discharge end of the casing adapted to be connected to the intake of an internal combustion engine, a member rotatably mounted within the casing, said member comprising a casting having a plurality of fuel conducting passages formed therein and extending from one end to the other through the casting, said casting being provided on its inner end with a central intake opening common to all of said passages, blades formed on said inner end of the casting, said blades radiating from said central opening, and fuel separating means at the 80 85 90 95 100 105 110 115 120 125 130

- discharge end of the casing and in operative tatably supported in the casing, blades formed on the member at one end of the member in operative relation to the intake opening of the casing, said member being provided with an intake opening, fuel conducting passages formed in said member and communicating at one end with the second mentioned intake opening, and a separator ring secured to the casing at its discharge end in operative relation to the discharge end of said passages, whereby a portion of the mixed fuel under pressure may be diverted rearwardly of the casing for co-mingling with the incoming fuel mixture, screen material arranged in each of said passages and extending transversely of the passages, and means within the casing cooperative with said suction blade for controlling the whirling motion of air within the casing.
6. In a gaseous fuel mixing device for internal combustion engines, a casing provided at one end with an intake opening adapted for communication with the discharge port of a carburetor, said casing at its opposite end being provided with a discharge opening adapted for communication with the intake of the internal combustion engine, a member rotatably supported in the casing, said member being provided at one end with a plurality of blades circumferentially arranged thereon, and disposed adjacent the intake opening of the casing, circumferentially spaced fins formed on the periphery of the member, and said member being provided with fuel conducting passages extending therethrough from one end to the other, and means interposed between the member and the discharge end of the casing whereby a portion of the fuel mixture discharging under pressure from said passages may be diverted to be returned through the casing to co-mingle with the incoming fuel mixture.
7. In a gaseous fuel mixing device for internal combustion engines, a casing provided with an intake opening at one end adapted for registry with the discharge opening of a carburetor, said casing at its opposite end being provided with a discharge opening adapted to register with the intake of an internal combustion engine, a member rotatably supported in the casing, blades formed on the member at one end of the member in operative relation to the intake opening of the casing, said member being provided with an intake opening, fuel conducting passages formed in said member and communicating at one end with the second mentioned intake opening, and a separator ring secured to the casing at its discharge end in operative relation to the discharge end of said passages, whereby a portion of the mixed fuel under pressure may be diverted to be returned rearwardly of the casing for co-mingling with the incoming fuel mixture.
8. In a gaseous fuel mixing device for internal combustion engines, a casing provided with an intake opening at one end adapted for registry with the discharge opening of a carburetor, said casing at its opposite end being provided with a discharge opening adapted to register with the intake of an internal combustion engine, a member ro-
- 15 20 25 30 35 40 45 50 55 60 65 70 75 80 85 90 95 100 105 110 115 120 125 130

means disposed in operative relation to said suction means and acting in opposition to said member to prevent whirling of the fuel mixture in said casing, and means adjacent the said opposite end of said member and disposed in operative relation to said passages for separating and diverting the wet particles of the fuel mixture discharged from said passages to be returned again under influence of said member.

10 In testimony whereof I affix my signature.
ELDEN ELMO BROWN.
